UNITED STATES PATENT OFFICE.

CLINTON H. SAWYER, OF NEW YORK, N. Y.

SPAR MILL.

1,414,306.

Specification of Letters Patent. Patented Apr. 25, 1922.

Application filed January 22, 1920. Serial No. 353,357.

To all whom it may concern:

Be it known that I, CLINTON H. SAWYER, a citizen of the United States, and a resident of the borough of Bronx, county, city, and 5 State of New York, have invented certain new and useful Improvements in Spar Mills, set forth in the annexed specification.

This invention relates to apparatus for shaping and finishing long ponderous articles such as masts, spars and columns. 10

The object of the invention is to make possible, with the greatest convenience and ease, the shaping and finishing of such an article through the medium of mechanical 15 power.

Such articles as masts and spars are shaped out of a natural log or tree-trunk and it has been found that turning, in which the cut is transverse to the grain, is not nearly 20 so satisfactory as shaping by draw-cutting in the direction of the grain. In carrying out the general object of this invention it is preferred to shape and finish the work with a rotary-cutting tool capable of making substantially a draw-cut. A further 25 object of the invention is to provide efficient and effectively operable means for automatically imparting any desired taper or other longitudinal contour to the workpiece.

A further object is to provide for the more 30 ready mounting of a log, its rotation about a fixed axis while it is being worked upon by the cutter and its support against sagging. A still further object of the invention 35 is to provide an apparatus capable of operating as described and in addition to be capable of shaping flat faces on articles such as a column or mast to the end that their entire body or any portion thereof may 40 be given a polygonal cross-section or a cross-section of any combination of surfaces of revolution and flat surfaces.

Such apparatus may best be termed a spar 45 mill and it is generally the objective to provide a spar mill of great adaptability and convenience in shaping masts, spars and columns varying greatly in size and shape.

The above will better be understood by 50 reference to the illustrative embodiment, to which the claims are directed merely for purposes of illustration, and which illustrative embodiment is described in the following specification in connection with the accompanying drawings which form a part hereof and in which like characters desig-

nate corresponding parts in the several figures.

In the drawings, Fig. 1 is a diagrammatic plan view showing a preferred layout for the mill;

Fig. 2 is a diagrammatic elevation, drawn to an enlarged scale and with parts broken away, of a layout of the mill;

Fig. 3 is a section along the plane of line III—III of Fig. 2, showing the tool truck 65 in elevation with parts broken away;

Fig. 4 is a sectional elevation through the center plane of the structure E of Fig. 2 but with parts shown in vertical cross-section through the tool carriage;

Fig. 5 is a side elevation of a driving-ring 70 chuck viewed from the plane of line V—V, in Fig. 2;

Fig. 6 is an enlarged section through the plane of line VI—VI of Fig. 5;

Fig. 7 is a detail side elevation of the 75 coupling for the removable section of the cradle-stock; and

Fig. 8 is an enlarged section through the plane of line VIII—VIII of Fig. 7 but with 80 parts broken away.

The trackway A comprises preferably three parallel straight tracks 1, 2 and 3 suitably laid, as on ties 4 in the usual manner in which track rails are laid. This track 85 forms what is usually known in a lathe as the bed. Adjustably mounted on this trackway are a plurality of stocks which may be termed cradle-stocks and which provide for the mounting and rotation of the workpiece 90 upon a fixed axis above and parallel to the said trackway. It is preferred that these stocks B comprise two end interchangeable head and tail stocks 5 and 6 and one or more intermediate ring chuck stocks 7 although it is to be understood that all of the stocks may be ring chuck stocks like 7, only one, or all of which are power-driven, as desired. Each of these stocks has supporting-feet 8 and 9 clampable by clamps 10

to the trackway A, preferably to the tracks 1 and 2, along which the stocks are individually adjustably movable to accommodate various lengths of workpieces and various desired positions particularly for the intermediate ring chuck stocks. Usually one central ring-chuck stock is sufficient and for heavy work the power rotation of the workpiece is through the medium of this central ring-chuck stock. A suitably constructed 110

cast-metal frame 11 has an openable section 12 mounted on the hinge 13 to swing up as indicated in dash lines in Fig. 5 through the medium of a tackle 14, secured 5 to the eye-bolt 15. This frame provides a circular guideway through the medium of the guide flanges 16 and 17, the faces of which are finished to guide the mating faces of the cast iron ring 18 with tracks therein. 10 The ring 18 is peripherally provided with a circular rack 19 with which the driving pinion 20 journalled in the frame 11 meshes and which can be driven in any suitable manner as by the pulley 21 and belt 22. The 15 ring 18 is provided with equi-angularly spaced radially projecting adjustable headed bolts 23 adjustable to clamp spider pieces 24 to the workpiece which may be adjusted to hold the workpiece in a central axial position. 20

The hinged openable section 12 may be releasably locked closed by the clamp-locks C. In the construction of these locks the machine spindle 30 is suitably fastened in a 25 half cylindrical cross-channel formed across the parting face of the end 31 of frame 11 in which it may be anchored in any suitable manner as by the bolt 32. The spindle 30 extends out on each side face of the frame 30 11 symmetrically and on the opposite sides of said frame symmetrical cups and split rings are provided. One portion 33 of the taper split ring is fixed to the end 11' of frame 11 while the portion 34 is fixed to the 35 end of the openable section, 12. The extending end 30' of the spindle 30 is co-axial with the split ring and, through the medium of the nut 35, serves to clamp the taper cup 36 against the two parts of the split ring 40 which draws the openable section 12 of the frame to seat on the machine spindle 30. Likewise the ring 18 has a removable section 37 which is removably secured to the main part of the ring 18 by split ring and cap 45 connectors c'. Registerable perforations 38 extending transversely through both removable sections 12 of the frame and 37 of the ring may be pierced by suitable pins 39 to hold the two removable sections assembled 50 so that when they are swung up as indicated in dash lines they move as an entity. It is to be understood that the pins such as the pins 39 are not to be inserted when the chuck is in operation, as it is then necessary that 55 the toothed rack 18 slide in the bearings 17 and 16. These pins are inserted only when the openable section 12 is to be lifted up, as shown in dotted lines in Fig. 5. Likewise, if desired, a jamb-bolt 40 may be provided, 60 as indicated in Fig. 6, to fix the ring-chuck 18 to the frame 11 as when the workpiece is to be held against rotation, as when cutting a flat face on a column.

A truck D of any suitable construction but 65 preferably a T-shaped frame 44 is mounted

upon double flanged wheels 41 and 42, 42 being driven on rail 3, and wheel 43 flanged or unflanged as desired although preferably cylindrical to track on rail 1. The truck frame 44 carries an upright 45 mounting an 70 electric motor 46 which is connected by belt 47 through pulley 48 to the worm 49 in mesh with worm wheel 50 which may be clutched or unclutched to the shaft-pinion 51 by the clutch 52, hand-wheel 53 being permanently 75 drivingly fixed to the shaft of pinion 51 which meshes with gear 53' to drive track wheel 42 to effect propulsion of the truck D. The frame 44 provides horizontal guides 80 54 on which is transversely movably mounted the base 55 of tool-carriage E. The base 55 has an upwardly projecting cylindrical flange 56, which seats piston-like boss 57 of the tool-carriage which may be raised or lowered by any suitable mechanism such as the screw 58. The boss 57 is cast integrally with the journals 59 mounting the tool spindle 60 which carries a rotary cutter 61 and is driven by the pulley 62 through belt 63 from the motor 64, motor 64 is mounted on 90 the flanged mounting 65 carried by the cylindrical boss 66 and with which adjustment may be made through any suitable means such as the screw 67, which is worked through the hand hole 68 by means of the 95 wheel 69, so that the belt 63 may be tightened as desired. The adjustable parts may be locked in position in any suitable manner as by set screws 70. A guard 71 to shield the cutter 61 is mounted on the stem 72. 100

The tool-carriage E has been described as transversely movable relatively to the truck D through the medium of the base 55 guided in the guideways 54. To move the carriage a weight 75 is attached to the free end of the tension cord 76 passing over pulley 77 which is journalled to the truck D. The other end of the cord 76 is attached to a suitable boss 78 formed on the carriage E so that the cord and weight form tension means reacting between the truck and the carriage tending to move the carriage to the right as viewed in Figs. 3 and 4. Journalled against axial movement in the boss 79 which is dependent from the base 55 is a feed-screw 80, squared at both ends for the reception of an operating handle. This feed-screw works in the internally threaded head of a follower 81 which has a slide bearing 82, fixable by set screws 83 to the guide rod 84, which passes through slide bearings 85 and 86 formed as upwardly projecting bosses from the truck frame 44. The rod 84 may be fixed to the truck frame by one or more set screws 87. A second slide bearing 88 is provided for the follower 81 and works on the guide bar 89 secured to the bosses 90 and 91. Dependent from the follower 81 is a guide block in the form of anti-friction roller 92 adapted to bear against the finished side face of 110 115 120 125 130

guide-rail 93 which is preferably flexible and may be formed conveniently out of wooden string pieces of suitable cross-section. This guide-rail 93 is fixed to adjustable brackets 94 each having a slot 95 through which a lag-screw 96 adjustably clamps the bracket to each cross tie 4. By loosening the screws 96 the guide-rail may be forced to assume any desired configuration, which is fixed by 5 tightening the screws, the wooden rail being sufficiently flexible and resilient for this purpose. The tension means 76, when either the set screws 87 or 83 are loosened serves to force the roller 92 against the side face of 10 the guide-rail 93, so that the rotary-cutter 61 is guided against the workpiece 100 to cut the same in the desired longitudinal contour or taper. The rotary cutter 61 may be fed either towards or from the workpiece independently 15 of the guide-rail 93 by turning the feed-screw 80 in the desired direction. Also, if desired, the follower 81 may be moved away from the guide-rail 93 and be fixed relatively to the truck by setting up the set screws 83 and 87. In this position the track 20 3 serves as the means for guiding the carriage E as well as the truck D and the feeding of the cutter 61 may be effected solely manually through the feed-screw 80.

25 A trolley construction F of any approved form and of sufficient units to supply the necessary circuits is carried by the truck D and cooperates with a set of trolley wires G which parallel the trackway A and supply energy for the motors 46 and 64 which may be controlled independently by suitable controllers 101 and 102. So far the truck D has been described as it is shown in Fig. 1. It is preferred however that for each mill two 30 trucks D and D' be provided, both running on the same trackway A and both fed by the same trolley installation. The truck D' is the exact symmetrical duplicate of the truck D, symmetry applying to the positioning 35 of the respective parts which individually are the same on one truck as on another, for example, the propulsion motor 46 of truck D is at the left as viewed in Fig. 1 while the same motor is at the right for truck D'. It 40 is for the construction, D, as shown particularly well in Fig. 2 that the rotary cutter 61 is free from all obstruction at its right hand side and may be brought close up against the driving stock B, when it is formed and positioned as shown in Fig. 2. In the same 45 way the truck D' may carry its rotary cutter 61' close up against the stock B when moving from right to left, that is against the right side of stock B as viewed in Fig. 2.

50 It is preferred, however, that the direction of rotation and the direction of the cutting faces of the rotary cutter 61' be exactly opposite from those of the cutter 61 and that the cutting travel be from left to right for truck D' and from right to left for truck D.

By this arrangement of two trucks, the cutting stroke may be commenced from very close to the driving grippers 24 and extend outwardly in both directions.

The head and tail stocks 5 and 6 may be 70 of any usual construction suitable for heavy work but preferably comprise a chuck 110 in addition to a removable center 111 (either alive or dead). Suitable circuit connections 75 112 are provided for the motors and it is to be understood that the trackway A may provide a return circuit or not according to the number of trolley units F provided.

What is claimed and what is desired to be secured by United States Letters Patent 80 is:

1. In a spar mill in combination, an earth bedded trackway comprising a plurality of straight parallel tracks; two or more work stocks for mounting a rotatable work-piece 85 each movably fastened to said trackway; a cutter-carriage mounting a laterally adjustable rotary cutter mounted to rotate on an axis transverse to the length of said trackway, said carriage having a longitudinal 90 movement along said trackway relatively to said work-piece; a guide-rail adjustably mounted along said trackway and presenting a laterally facing guide-face to control the lateral adjustment relatively to said 95 work-piece of said rotary cutter; and means operatively connected with said rotary cutter and adapted to run along said laterally facing guide-face automatically to adjust the lateral position of said rotary cutter 100 relatively to said work-piece as said carriage travels along said trackway.

2. In a spar mill in combination, a trackway comprising a plurality of straight parallel tracks; two or more work stocks for 105 mounting a rotatable work piece each movably fastened to said trackway; a cutter carriage mounting a laterally adjustable rotary cutter and mounted for longitudinal movement along said trackway relatively to said 110 work piece; a cutter carriage guide rail adjustably mounted along said trackway and presenting a laterally facing guideface to control the lateral adjustment of said rotary cutter; and adjusting means operatively 115 connected with said rotary cutter and adapted to run along said laterally facing guideface to adjust the lateral position of said rotary cutter relatively to said work piece as said cutter carriage travels along said trackway.

3. In a spar mill in combination, a straight trackway; a plurality of rotary work stocks longitudinally adjustably mounted on said trackway and each having a work-gripping part, one of said stocks comprising a frame providing a circular guide way at right angles to said trackway, having a lateral openable section, a ring-chuck working in said circular guideway 125 130

- and having an openable section whereby work may be rolled laterally into said ring-chuck; means for rotating a work-gripping part of one of said stocks; a cutting tool; 5 and means for carrying said cutting tool along the work to be cut.
4. In a spar mill in combination, a trackway; a plurality of work stocks longitudinally adjustably mounted on said trackway; 10 one of said stocks comprising a cradle-frame providing a circular guideway at right angles to said trackway, having a lateral openable section, a ring-chuck working in said circular guideway, itself having an openable 15 section and being provided with a circular rack and a driving pinion for said rack journalled in said cradle-frame; a cutting tool; and a carriage for carrying said cutting tool along the work to be cut.
- 16 5. In a spar mill; a cradle-chuck, said chuck comprising a frame providing a circular guideway and having a laterally hinged section, means for holding said hinged section closed comprising a cup and 20 split-ring construction, the portions of the split-ring being secured to the fixed and openable portions of said frame respectively.
6. In a spar mill in combination, a straight 25 trackway comprising parallel tracks; an adjustable guide rail extending along said trackway; a plurality of work stocks adjustably mounted on said trackway; a truck movable on said trackway and held thereto 30 against transverse movement; a tool carriage transversely movably carried by said truck and a follower secured to said carriage and engaging said guide-rail to control the transverse movement of said carriage as said truck moves along said trackway.
7. In a spar mill in combination a straight 35 trackway comprising parallel tracks; an adjustable guide rail extending along said trackway; a plurality of work stocks adjustably mounted on said trackway; a truck movable on said trackway and guided thereon against transverse movement; a tool carriage transversely movably mounted on said 40 truck; a follower for engaging said guide rail automatically to control the transverse adjustment of said carriage as said truck moves along said trackway; and hand-adjustable connection between said follower 45 and said carriage for making an adjustment of said follower, relatively to said carriage.
8. In a spar mill in combination a straight trackway comprising parallel tracks; an adjustable guide rail extending along said trackway; a plurality of work stocks adjustably mounted on said trackway; a truck movable on said trackway and guided thereon against transverse movement; a tool carriage transversely movably mounted on said truck; a follower for engaging said guide rail automatically to control the transverse adjustment of said carriage as said truck moves along said trackway; a hand-adjustable connection between said follower and said carriage for making an adjustment of 50 said follower relatively to said carriage; and means for rendering said hand-adjustable connection operative independently of said follower and guide rail for adjusting the transverse positioning of said tool carriage.
9. In a spar mill in combination, a trackway, means mounted along said trackway for rotatively mounting a workpiece on an axis parallel to said trackway; a truck movable along said trackway and comprising wheels in engagement with said trackway; a motor; means for disengagingly gearing said motor with one of said wheels; a tool-carriage transversely movably mounted on 55 said truck and having a guide-block; an adjustable guiderail mounted along said trackway; and tension means reacting between said truck and said carriage tending to force said guide-block against said guiderail to guide said carriage transversely to said trackway.
10. In a spar mill in combination, a trackway; rotary work stock adjustably mounted on said trackway; a work-tool carrying truck running on said trackway; an electric motor on said truck for driving it along said trackway; and one or more trolley conductors paralleling said trackway for supplying energy to said motor.
11. In a spar mill in combination a trackway; a head and a tail stock spaced along said trackway; an intermediate ring-chuck mounted on said trackway, adapted to rotate the work-piece; two trucks running on said trackway and mounting each a propelling motor and a cutter-blade, said trucks being formed symmetrically with respect to said ring-chuck having the cutting tool of each 60 said truck free to reach said ring-chuck each from an opposite side.

CLINTON H. SAWYER.
